UNITED STATES PATENT OFFICE.

GUY B. WAITE, OF NEW YORK, N. Y.

EXTENSIBLE CENTERING-SUPPORT.

SPECIFICATION forming part of Letters Patent No. 770,618, dated September 20, 1904.

Application filed July 5, 1904. Serial No. 215,329. (No model.)

To all whom it may concern:

Be it known that I, GUY B. WAITE, a citizen of the United States, residing in the city, county, and State of New York, have invented 5 certain new and useful Improvements in Extensible Centering-Supports Employed in the Construction of Arches, of which the following is a specification.

My invention relates to an improved form 10 and construction of temporary centering-supports used in the construction of arches of concrete, masonry, and the like.

My present invention relates to the same 15 general subject-matter as is disclosed in Letters Patent No. 724,146, granted to me March 31, 1903, being in the nature of an improvement upon the construction disclosed in the said patent. In accordance with the aforesaid patent I have extensively employed in the 20 construction of arches a support for the lagging consisting of a pair of wooden ribs disposed side by side and each having fixed to one end a laterally-extending rest-piece, on which the adjacent end of the other rib is slidably 25 supported with the ends of the rest-pieces or other extension members of the ribs stepped on the lower flange of the permanent I-beam supports of the arch. I have found in practice that the ends of these rest-pieces or ex- 30 tension members usually leave considerable of a hole in the concrete when removed and being permanently secured to the ribs render necessary the use of separate sets of ribs and rest-pieces for arches of varying heights.

35 It is the object of my present invention to improve upon this construction in the way of presenting a smaller obstruction to the concrete filling and enabling the same ribs and rest-pieces to be employed in the construction 40 of arches of varying heights.

To these ends my invention consists, generally stated, in the combination, with the centering-ribs and laterally-extending rest-pieces secured to the lower edges thereof at their 45 opposite ends, of detachable suspension-hooks, secured to said rest-pieces and considerably narrower than the latter, adapted to engage the lower flange of the permanent I-beam or

other supports of the arch, and thus support the ribs from the latter.

50 My invention further consists in a novel means for securing the rest-pieces to the ribs in such a manner as to insure against their accidental separation under unusual strain, such means consisting of a wire or strap in the 55 form of a loop carried over and around the rib and secured to or near the rear end of the rest-piece, thus tying the latter to the rib by a tension member capable of resisting the maximum strains to which the ribs are ever subjected in practice.

I have illustrated my invention in the accompanying drawings, wherein—

Figure 1 is a vertical cross-section through 65 that portion of an arched fireproof floor of concrete or the like lying between two adjacent I-beams, showing my improved centering structure in side elevation therein. Fig. 2 is a similar view, broken away intermediate the I-beams, of a similar structure adapted for the 70 formation of a low or "flat" arch. Fig. 3 is a top plan view of Fig. 1, omitting the concrete and lagging. Fig. 4 is a perspective view of 75 one end of the companion ribs and their supporting means; and Fig. 5 is a perspective view of the parts shown in Fig. 4 at a different angle, illustrating the means and manner of attachment of the rest-piece to the rib and of the hanger to the rest-piece.

Referring to the drawings, 10 designates 80 the usual I-beams or girders, constituting permanent supports for the arch.

11 designates an arched filling of concrete, cement, or other fireproof material. To support this material as it is laid in place, I employ a series of transverse ribs disposed side by side in pairs, said ribs being designated by 12 and themselves directly supporting the lagging-strips 13.

14 designates each of a pair of what I term 90 "rest-pieces," secured to opposite ends, respectively, of the two ribs, each of said rest-pieces extending laterally of the rib to which it is secured sufficiently to constitute a direct rest or support for the adjacent end of the other rib 95 with capacity for the latter to slide thereover

a limited distance to suit the distance between the I-beams, all as fully disclosed in my former patent above referred to.

Heretofore and at present in the case of 5 comparatively short ribs the rest-pieces may be and are secured to the latter by nailing or screwing them in place, as indicated at 15. In the case of long ribs and ribs subjected to unusually heavy loads, however, there is danger that the rest-pieces may break away from 10 the ribs before the arch is completely filled in or set, and to obviate this danger one feature of my present improvement consists in the employment of a loop 16 of wire or strap 15 metal, which is fitted around the rib with its lower ends passed through apertures in or carried around the rear end of the rest-pieces and then turned inwardly and nailed, twisted together, or otherwise secured to or beneath 20 the rest-piece, as plainly shown at 17 in Fig. 5. By this means that portion of the rest-piece subjected to the greatest strains tending to disrupt it from the rib is securely united to the latter by a tension member easily capable of resisting such strains without interfering with the operation of the companion rib.

In order to support the ribs and rest-pieces from the I-beams, I employ narrow bent iron suspension hooks or hangers 18, which are 30 nailed by their lower horizontal portions 18^a to the under side of the outer end of the rest-piece approximately coincident with the transverse center of the latter, as shown at 19 in Figs. 1 and 5, their vertical portions lying opposite the end of the rest-piece and rib and 35 their outer projecting lips 18^b taking over the lower flange of the I-beam. As illustrated in Figs. 1 and 2, these suspension-hooks will be made of varying heights, according to the various heights of arches to be served by the 40 ribs, and with a given set of ribs and rest-pieces permanently secured thereto all that is necessary to adapt the ribs to an arch of any given height is to select from among the 45 hooks such as are of the height required and nail or otherwise secure them to the rest-pieces, removing and replacing them by lower or higher hooks for subsequent uses as to the particular formation of subsequent arches 50 may necessitate. The arch shown in Fig. 1 is a high arch, and consequently the hooks 18 required therefor are low or short. The arch served by the construction shown in Fig. 2 would be a low or flat arch, which would 55 require the use of a long or high hook 18'. Obviously intermediate arches would require hooks intermediate the dimensions represented in these two figures. The hooks as herein shown are narrow and rectangular in 60 cross-section; but it is obvious that the vertical and upwardly-projecting portions of the hook would serve equally well if made of round metal. Preferably the vertical portion

of the hook is carried up in direct face contact with the outer end of the rest-piece and 65 rib to the extent that it follows the latter, this disposition of the parts contributing to increased rigidity and strength of the structure as a whole. This, however, is not essential, and the upright member of the hook may be 70 more or less separated from the end of the rib to provide more space for lagging or concrete when desired.

While I have shown and described the upper bent ends of the hooks as adapted to take 75 over and rest upon the flanges of the permanent I-beam supports and contemplate such as their principal mode of use, yet such a manner of supporting the hooks is not of the essence of the invention. In some cases side 80 boards running parallel with the I-beams on either side of and suspended from the latter are employed, and in such cases the upper ends of the hooks would hook over the upper edges of such side boards. My invention also 85 is not concerned with any particular form or contour of centering-ribs. For convenience and brevity of illustration I have shown only plain rectangular ribs; but it is obvious that the herein-described rib supporting and suspending means are applicable to other forms 90 of ribs, such as curved ribs or ribs having straight intermediate portions and rounded or cut-down ends.

I claim—

1. In a centering-support for arches, the combination with a pair of ribs disposed side by side and longitudinally adjustable relatively to each other, of rest-pieces secured to opposite ends of said ribs, respectively, each 100 adapted to support the adjacent end of the companion rib, and suspension-hooks secured to said rest-pieces and extending upwardly and forwardly of the ends of the ribs, substantially as described.

2. In a centering-support for arches, the combination with a pair of ribs disposed side by side and longitudinally adjustable relatively to each other, of rest-pieces secured to the lower edges of said ribs at opposite ends thereof, respectively, each adapted to support the adjacent end of the companion rib, and narrow suspension-hooks secured to the under sides of said rest-pieces, and extending upwardly and forwardly of the ends of the ribs, substantially as described.

3. In a centering-support for arches, the combination with a rib and a rest-piece for the adjacent end of a companion rib extended laterally from the lower edge of said first-named rib, of means for securing said rest-piece to said rib consisting of a metal loop or band embracing said rib and rest-piece and constituting a tension-bond between said parts, substantially as described.

4. In a centering-support for arches, the

combination with a rib and a rest-piece for the adjacent end of a companion rib extended laterally from the lower edge of said first-named rib, of means for securing said rest-piece to said rib consisting of a metal loop or band embracing said rib and rest-piece through apertures in the latter and constituting a ten-

sion-bond between said parts, substantially as described.
